FASHIONING MECHANISM FOR KNITTING MACHINES

Kurt P. Bauer, Wyomissing, Pa., assignor to Textile Machine Works, Wyomissing, Pa., a corporation of Pennsylvania

Application September 2, 1954, Serial No. 453,793

21 Claims. (Cl. 66—89)

This invention relates to improvements in straight knitting machines for knitting fashioned stocking or other blanks and more particularly to mechanism for universally controlling the fashioning mechanism of such machines.

In straight knitting machines of the type for knitting fashioned fabric blanks such as stockings, the selvage edges of the blanks are fashioned by varying the endwise movement of the yarn carrier rods and the narrowing point combs. The endwise movement of the carrier rods is controlled by end stop devices carried on threaded spindles and the point combs are moved by nuts also carried on threaded spindles. The spindles are rotated in either direction to vary the position of the stop devices and comb operating nuts by pawl and ratchet devices. In the usual practise, the spindles for the carrier rod stop devices are moved in either direction in two needle steps and the spindles for operating the point comb nuts are moved in the narrowing direction in one or two needle steps and in the widening direction in one needle steps. Also, the point comb nuts are moved idly in the widening direction in one needle steps. The sequence of operations of the point comb nuts and particularly the idle movements of the nuts is frequently varied to produce different fashioning mark effects along the edges of the fabrics. The movement of the spindles for the various fashioning operations is controlled by selecting means, which in turn is in part controlled by the movement of the end stop devices and in part by the pattern chain devices of the machine. However, in the known machines each variation in the sequence of steps to fashion the selvage edges of the blank usually requires extensive changes in the selecting means in addition to a rearrangement of certain of the control buttons on the pattern chain resulting in a considerable loss in time and production.

Also, during the fashioning of the various parts of the blanks, the combs must be repositioned to vary the number of points in the fashioning process. To so vary the position of the point combs, the spindles must be manually rotated, which action is performed several times during the production of each set of blanks and at the completion of a set of blanks, the spindles must be similarly manually rotated to return the carrier rod end stops and the narrowing point combs to starting position for the start of the next set of blanks.

It is an object of the present invention to provide novel means in a straight knitting machine which permits a variation in the fashioning sequence without changing the operating and controlling parts and with a minimum of time spent in adjustments of the machine.

Another object of the invention is to provide means to automatically reset the point combs of a full-fashioned knitting machine for knitting stocking or other fabric blanks to vary the number of narrowing points in the fashioning operation in the different portions of the blanks.

A further object of the invention is to provide means

2

in a full-fashioned knitting machine for automatically controlling the operation of the narrowing mechanism to fashion stocking fabric blanks, to reset the narrowing mechanism to perform the different fashioning operations, and to return the narrowing mechanism to starting position at the completion of the fabric.

With these and other objects in view which will become apparent from the following description and the accompanying drawings, the invention resides in the novel elements, features of construction and arrangement of parts in cooperative relationship as hereinafter more particularly pointed out in the claims.

In the drawings:

Figure 1 is an elevational view of the left end of a full-fashioned knitting machine embodying mechanism for controlling the operation of the fashioning spindles according to the invention;

Fig. 46 is a cross sectional view taken along the line 46—46 of Fig. 45;

Fig. 47 is a detailed view, partially in elevation and partially in section taken substantially along the line 47—47 of Fig. 44; and

Fig. 48 is a cross sectional view taken along the line 48—48 of Fig. 47.

The mechanism illustrated in the drawings comprises portions of the left end of a full-fashioned knitting machine embodying the novel features of the invention. It will be understood that the right end of the machine is similar in structure and operation but in reversed position. More specifically the mechanism illustrated includes the usual threaded spindle for the end stops, pawls

and ratchets for turning the spindle in either direction, an actuator member for the pawls, cams for determining the operation of the actuator member and pattern means for controlling the operation of the cams. The pawls are controlled and operated to turn the spindle a distance equal to a two needle spacing in either direction on both the upstroke and downstroke of the actuator. Electrically controlled means is also provided to reset the end stop spindle to position it for the start of a new set of stocking blanks subsequent to the completion of a set of stocking blanks.

The mechanism also includes a threaded spindle for the narrowing point combs, pawls and ratchets for turning the spindle in either direction, cam members for determining the operation of the pawls, and pattern means for controlling the operation of the cam members. The pawls are operated by an actuator member which in turn is operated from the camshaft of the machine. The pawls are controlled and operated to turn the spindle one to three needles in either direction on both the upstroke and downstroke of the actuator.

Referring to the drawings and more particularly Figs. 1, 29 and 30, there is shown the left end portion of the framework of a usual multi-section full-fashioned knitting machine having transverse end frames, one of which is shown at 60, transverse center frames 61, a front beam 62, a back beam 65, a center bed 66 and a front bed (not shown), said beams and beds extending lengthwise of the machine and connecting the end and center frames to each other. The machine framework supports elements including needles, sinkers and dividers for forming and knitting yarns laid by yarn carriers (not shown) into loops to form stocking fabric blanks. The framework also supports a main pattern chain mechanism 70 including usual cams 71 and 72 for shifting a main camshaft 75 between knitting and fashioning positions in the conventional manner. The machine is also provided with a narrowing or fashioning head mechanism for controlling the extend of travel of carrier rods which support the yarn carriers, and for controlling the endwise movement of the rods on which point combs are mounted to fashion the selvage edges of the blanks knitted on the machine.

A narrowing head mechanism according to the instant invention (Figs. 1, 2 and 3) is indicated at 80 and includes a threaded spindle 81 having a nut 82 mounted thereon which is provided with a series of usual end stop members 85 (Fig. 41), one for each of the carrier rods (not shown) of the machine. The narrowing head mechanism 80 also includes a spindle 86 having reversely threaded portions on each of which is mounted a nut 90 for controlling the movement of rods 89 (Fig. 1) for point combs (not shown) in the usual manner, only the left nut 90 and left threaded portion of the spindle being shown in the drawings.

Each end of the spindle 81 is supported for rotation in brackets, one of which is shown at 91 and each end of the spindle 86 is supported for rotation in brackets, one of which is indicated at 92. The brackets 91 and 92 are carried on a base plate 95 mounted on the center bed 66 (Fig. 4). As hereinbefore set forth the narrowing head mechanism 80 illustrated in the drawings is at the left end of the machine, it being understood however, that a similar mechanism is also provided at the right end of the machine.

The spindles 81 and 86 are rotated in a clockwise direction to move the nut 82 for the end stop members 85 and the nuts 90 for the point comb rods inward to narrow the fabric and are rotated in a counterclockwise direction to move the nuts outward to widen the fabric. In the machine shown, four rods 89 (Fig. 1) are operated by the spindle 86 to fashion the stocking fabrics, two of the rods having wide point combs thereon and the other two rods having narrow point combs thereon although it is also common practise to use only two rods each having only wide point combs. Where wide and narrow point combs

are used, one wide and one narrow comb function as a pair at one selvage edge of each stocking fabric knitted on the machine and the other wide and narrow combs function in pairs at the other selvage edges of the fabrics. In either instance, the rods 89 for the wide combs are connected to the nuts 90 for positive movement therewith in opposite directions. The rods for the narrow combs are normally connected to the nuts 90 for movement only in the narrowing direction. In many of the present full-fashioned knitting machines, having both wide and narrow point combs, means are also provided to releasably connect the rods for the narrow combs to the nuts 90 for movement in opposite directions so that the pairs of wide and narrow combs function at times as single wide combs to fashion certain portions of the fabrics. However, the use of either point comb arrangement and the actual function of the combs to fashion the fabrics forms no part of the present invention and is only generally referred to in relation to the novel mechanism for turning the spindles as hereinafter set forth.

For rotating the spindle 81 in the clockwise direction the spindle is provided with a ratchet or ratchet wheel 96 (Fig. 10) having a tooth spacing to rotate the spindle and move the nut 82 a distance equal to two needle spaces. The ratchet wheel 96 is acted upon by a pawl 97 which is pivotally mounted on a pin 100 fixed in the free end of a lever 101 (Fig. 4) pivotally mounted on one end of the spindle 81. The pawl 97 is biased toward the ratchet wheel 96 by a spring 98 which is connected between the pawl and a member 99 (Fig. 17) which is fixed on the pin 100. The lever 101 is given an oscillating movement on the spindle 81 to move the pawl 97 sufficiently to rotate the ratchet wheel 96 and spindle one tooth of the ratchet wheel. For this purpose the lever 101 is pivotally connected by a pin 102 to one end of an actuator member 105 which is pivotally connected at its other end to one arm 106 of a forked lever 107 by means of a pin 110, as shown in Figs. 4 and 5. The arm 106 and a second arm 111 of the lever 107 are pivotally mounted on a shaft 112, fixed in a bracket 115 secured to the end frame 60, between collars 116 (Fig. 5) secured to the shaft.

The arm 111 of the lever 107 carries a pin 117 (Fig. 6) which pivotally carries one end of a link 120, the other end of the link being pivotally connected to a stud 121 adjustably secured in the free end of a cam lever 122. The cam lever 122 is pivotally mounted on a stud 125 secured in the end frame 60 and carries a shaft 126 on which a roller type follower 127 is rotatably and slidably mounted. A spring 130 surrounding the shaft 126 normally biases the follower 127 to a position intermediate cams 131 and 132 carried on the camshaft 75, in which position the follower is out of the path of both cams. The lever 122 is provided with an adjustable bolt 135 which is adapted to engage a portion of the end frame 60, as shown in Figs. 4 and 6, to determine the rest position of the lever and follower 127. The lever 122 is biased to said rest position by a spring 136 which is connected between the free end of the lever and the end frame 60. With this arrangement, when the spindle 81 is to be rotated to narrow the fabric, a narrowing or fashioning cycle is instituted by the pattern chain 70 in the usual manner which causes the cams 71 and 72 to shift the camshaft 75 toward the right, as viewed in Fig. 29 or in the direction of the arrow in Fig. 5, to move the cam 131 into alignment with the follower 127. As the camshaft is rotated, the cam 131 engages and moves the follower 127 and lever 122 upwardly which in turn gives the actuator 105 an "up" movement to move the lever 101 and pawl 97 to turn the ratchet 96 and spindle 81 clockwise a distance equal to one tooth of the ratchet, as viewed in Fig. 10.

The spindle 86 is turned in the clockwise or narrowing direction by a pawl 137 which acts on a ratchet wheel 140 (Fig. 12) secured to the end of the spindle, the teeth of the ratchet wheel having a spacing to move

the nut and point combs a distance equal to one needle space. The pawl 137 is pivotally mounted on a pin 141 fixed in the free end of a lever 142 pivotally carried on one end of the spindle 86. The pawl 137 is biased toward the ratchet wheel 140 by a spring 145 which is connected between the pawl and an anchor member 146 fixed on the pin 141, as shown in Figs. 22 and 25. To move the lever 142 an arm 147 thereof has a pivotal connection to one end of an actuator member 150, the other end of which is pivotally connected by a pin 151 to an arm 152 of a forked lever 155. The lever 155 is pivotally mounted on a shaft 156 fixed in a bracket 157 secured to the end frame 60 by bolts 158 (Fig. 4), the lever being positioned on the shaft between collars 160 (Fig. 5).

The lever 155 carries a pin 161 on which one end of a link 162 is pivotally mounted (Fig. 8), the link having its other end pivotally carried on a pin or stud 165 adjustably carried in the free end of a cam lever 166. The lever 166 is also pivotally mounted on the stud 125 and carries a shaft 167 on which a roller type follower 170 is rotatably mounted. A spring 171, surrounding the shaft 167, biases the follower 170 to a position on the shaft intermediate cams 172 and 175 on the camshaft 75, in which position the follower is out of the path of both cams, as shown in Figs. 5 and 7. The lever 155 carries an adjustable set screw 176 which is adapted to engage a portion of the end frame 60, as shown in Fig. 8, to determine the rest position of the levers 155, 166 and follower 170. The levers are biased to the rest position by a spring 177 connected between the arm 152 of lever 155 and the end frame 60 (Figs. 1 and 5). When the spindle 86 is to be rotated to move the point combs to narrow the fabric, the camshaft 75 is shifted as hereinbefore set forth to move the cam 172 into alignment with the follower 170. Upon rotation of the camshaft 75 the cam 172 engages the follower 170 to move it and the levers 166 and 155 upwardly which in turn gives the actuator 150 an "up" movement to move the lever 142 and pawl 137 to turn the ratchet 140 and spindle 86 clockwise as viewed in Fig. 12.

To supplement the action of the pawls 97 and 137 to turn the spindles 81 and 86, respectively, in the narrowing direction on the "up" stroke of the actuators 105 and 150, at certain times, as hereinbefore set forth, means are provided to also turn the spindles in the narrowing direction on the "down" movement of the actuators and cam levers 122 and 166 to the rest position. For the purpose of moving the spindle 81 in the narrowing direction on the downstroke of the actuator 105 a pawl 180 is provided having a nose piece 181, for engaging the teeth of ratchet wheel 96 the nose piece being adjustably secured to the pawl (Fig. 10). The pawl 180 is pivotally mounted on a pin 182 fixed in a lever 185 (Fig. 4) pivotally mounted on the end of the spindle 81 adjacent to the lever 101. The pawl is biased toward the ratchet wheel 96 by a spring 186 which is connected between the pawl and an anchoring member 187 fixed on the pin 182 (Fig. 18). The lever 185 has a portion 190 extending to the right of the spindle 81 which has a pivotal connection to one end of a link 191 the other end of which is pivotally connected to the actuator 105, as shown in Fig. 4. During the "up" stroke of the actuator 105 the lever 185 and pawl 180 is moved counterclockwise around the spindle 81, as viewed in Figs. 4 and 10.

When the actuator 105 is moved downwardly as the cam lever 122 is returned to rest position, the pawl 180 when permitted to engage the teeth of the ratchet 96 will turn the spindle in the narrowing direction. Therefore, with this arrangement the pawl 97 may act to rotate the spindle 81 a distance equal to two needle spaces in the narrowing direction on the "up" movement of the actuator 105 and/or the pawl 180 may act on the ratchet to move the spindle a distance equal to two needle spaces in the same direction on the "down" movement of the

actuator whenever the camshaft 75 is shifted to its narrowing position. The pawl 180 also acts as a means to hold the spindle 81 in the positions to which it is moved by the pawl 97, as hereinafter set forth.

For moving the spindle 86 on the downstroke of the actuator 150 a pawl 192 is provided having a nose piece 195 adjustably secured thereto for engagement with the teeth of the ratchet wheel 140. The pawl is pivotally carried on a pin 196 fixed in a lever 197 (Figs. 4 and 12) pivotally mounted on the end of the spindle 86 adjacent to the lever 142. The pawl 192 is biased toward the ratchet wheel 140 by a spring 200 which is connected between the pawl 192 and an anchoring member 201 secured on the pin 196, as shown in Fig. 26. The lever 197 is pivotally connected to one end of a link 202 by means of a pin 205, the other end of the link being pivotally connected to the actuator 150 (Fig. 4). During the "up" stroke of the actuator 150 the lever 197 is moved counterclockwise on the spindle 86, as viewed in Figs. 4 and 12. When the actuator 150 is moved "down" as the lever 166 is returned to rest position, the pawl 192, when permitted to engage the teeth of the ratchet wheel 140, will turn the spindle 86 in the narrowing direction. With this arrangement, the pawl 137 may act to rotate the spindle 86 in the narrowing direction on an "up" movement of the actuator 150 and/or the pawl 192 may act to rotate the spindle in the narrowing direction on a "down" movement of the actuator when the camshaft 75 is in its narrowing position. Each of the pawls 137 and 192 are controlled to move the spindle 86 a distance equal to one, two or three needle spaces and the pawl 192 also is controlled to hold the spindle in the position to which it is moved by the pawl 137 by means hereinafter set forth.

As hereinbefore set forth, the spindles 81 and 86 are moved in a counterclockwise direction to move the nuts 82 and 99, respectively, outwardly to widen the fabric. The spindles may also be moved in the counterclockwise direction for the purpose of resetting the spindles as hereinafter set forth. For moving the spindle 81 in the counterclockwise direction the spindle has a ratchet wheel 206 fixed on the end thereof having a tooth spacing similar to the ratchet wheel 96. The ratchet wheel 206 is acted on to turn the spindle 81 by a pawl 207 which is pivotally mounted on the pin 182 in the lever 185. The pawl 207 is biased toward the ratchet wheel 206 by a spring 210 connected between the pawl and the anchoring member 187, as shown in Figs. 9 and 13.

In the usual practice, the spindle 81 is rotated in the counterclockwise direction to move the end stops for the carrier rods outwardly during a knitting cycle at which time the camshaft 75 is positioned as shown in Figs. 5 and 7. In order to rotate the spindle 81 in the counterclockwise direction, the follower 127 is shifted on the shaft 126 into alignment with the cam 132 which acts on the follower, lever 122 and actuator member 105 to operate the pawl 207 on the "up" stroke of the actuator member. The follower 127 is shifted by means of an arm 211 of a lever 212 which is pivotally carried on a pin 215 fixed in a bracket 216 mounted on the back beam 65. The lever 212 is oscillated on the pin 215 to shift the follower 127 into alignment with the cam 132 on the camshaft, by a link 208 one end of which carries a collar 209 having pushing engagement with the arm, as shown in Fig. 7. The link 208 is pivotally connected to one arm 213 of a bell crank 214 pivoted on a bracket 218 secured to the frame 60 (Fig. 33). A second arm 219 of the bell crank 214 (Fig. 7) is connected by a link 223 to a pattern lever 224 pivoted on a shaft 198 forming a part of a pattern chain device 199 (Figs. 1, 29 and 33), the construction and operation of which is hereinafter set forth in detail. The pattern lever 224 is provided with an adjustable bit 228 for engagement with buttons 203 on a chain 204 (Fig. 34) forming a part of the pattern chain device 199. When a button 203 is beneath the lever 224 the link

208 and collar 209 are moved to shift the follower 127 to align it with the cam 132. When no button is beneath the lever 224 it rests on a set screw 229 adjustably carried on the bracket 218, the lever being biased to such rest position by a spring 233 which is connected between the lever and the frame 60, as shown in Fig. 33.

At certain times and particularly during the knitting of lace fabric, the camshaft 75 is shifted to its narrowing position but no turning movements of the spindle 81 are desired. Therefore, in order that the cam 131 will not be aligned with the follower 127 when the camshaft 75 is shifted, the follower is also moved to maintain its position intermediate the cams 131 and 132, as shown in Fig. 7. For this purpose the lever 212 is provided with a portion 217 extending at substantially a right angle to arm 211 the end of the portion being adapted to engage a collar 220 fixed on a rod 221 mounted for sliding movement along the back beam 65 in brackets carried on the back beam, one of the brackets being shown at 222 in Fig. 32. The end of the arm 217 is resiliently maintained in engagement with the collar 220 by a spring 225 connected between the arm and a collar 226 on the rod 221. The rod 221 may be shifted to the right as viewed in Fig. 32 to shift the lever 212 and follower 127 when the camshaft 75 is shifted to thereby maintain the follower intermediate the cams 131 and 132 as viewed in Fig. 7.

For shifting the rod 221 to the right the rod carries a block member 227 which is engaged by one arm 230 of a lever 231 pivotally mounted on a bracket 232 fixed on the back beam 65 (Fig. 31). A second arm 235 of the lever 231 is pivotally connected by a universal linkage 236 to one end 237 of a cam lever 240 which is pivotally carried on a pin or shaft 241 in the bracket 232 (Fig. 31). An arm 239 of the lever 240 rotatably carries a roller type follower 242 for engagement with a cam 245 on the camshaft 75 when the latter is in its shifted position, the follower being biased toward engagement with the cam by a spring 246 connected between the lever and a fixed part of the machine. The arm 239 is normally supported in its position of Fig. 31 by a support lever 247, the arm being moved to such position by the high part of the cam 245. The lever 247 is pivotally mounted on a bracket 250 secured to the front beam 62 and is connected by a rod 251 to a lever 252 which is operated by one of a series of pattern levers 253 forming part of the pattern chain mechanism 70, as shown in Fig. 29.

To institute a shifting movement of the rod 221, a button on the pattern chain mechanism 70 operates the levers 253 and 252 to remove the support lever 247 from beneath the arm 239 of the lever 240. As the camshaft 75 is rotated the follower 242 rides from the high portion to the low portion of the cam 245 which turns the lever 240 clockwise as viewed in Fig. 31 and the lever 231 counterclockwise as viewed in Fig. 32 to thereby shift the rod 221 to the right. When the high portion of the cam 245 is again beneath the follower 242, the support lever 247 is returned to its position beneath the arm 239 to again maintain the levers 231 and 240 in their positions in Figs. 31 and 32. To maintain the member 227 in engagement with the end 230 of the lever 231 at this time, the rod 221 is biased to the left, as viewed in Fig. 32, by a spring 254 positioned on the rod between one of the brackets 222 and a collar 255 on the rod.

The spindle 86 is turned in the counterclockwise direction by engagement of a pawl 256 with a ratchet wheel 257 (Fig. 11) which is secured to the end of the spindle with and having the same tooth spacing as the ratchet wheel 140. The pawl 256 is pivotally mounted on the pin 196 and is biased toward the ratchet wheel 257 by a spring 260 which is connected between the pawl and the member 201 (Fig. 21). As hereinbefore set forth, the pin 196 is carried in the lever 197 which is connected to the actuator member 150 by the link 202. The actuator member 150 is connected to and operated by the lever 166 to move the pawl 256 on the "up" stroke of the actu-

ator member to turn the spindle counterclockwise or in the widening direction when the pawl is permitted to engage the teeth of the ratchet wheel 257.

Normally the lever 166 is operated by the cam 172 to actuate the pawl 256 and turn the spindle 86 in the widening direction when the camshaft 75 is shifted to its narrowing position. However, it is also desired to turn the spindle 86 in the widening direction, as hereinafter set forth, when the camshaft 75 is in its knitting position. For this purpose the follower 170 is adapted to be shifted on the shaft 167 against the bias of the spring 171 to align it with the cam 175 on the camshaft 75. The follower 170 is shifted by one arm 261 of a lever 262 which is pivotally mounted on a pin 265 also carried in the bracket 216. The lever 262 is oscillated on the pin 265 to shift the follower 170 into alignment with the cam 175, by a link 263 one end of which carries a collar 264 having pushing engagement with the arm 261 (Fig. 7). The link 263 is pivotally connected to one arm 268 of a bell crank 269 pivoted on the bracket 218 adjacent to the bell crank 214 (Figs. 7 and 33). A second arm 273 of the bell crank 269 is connected by a link 274 to a pattern lever 278 pivotally mounted on the shaft 198. When a button 203 on the chain 204 is beneath the pattern lever 278 the link 263 and collar 264 are moved to shift the follower 170 to align it with the cam 175. When no button is beneath the lever 278 it rests on one of the set screws 229, the lever being biased to such rest position by a spring 279 which is connected between the lever and the frame 60 (Fig. 33).

When the camshaft 75 is shifted to the narrowing position for the knitting of lace fabric, as hereinbefore set forth, it is also necessary to maintain the position of the follower 170 intermediate the cams 172 and 175 (Fig. 7) so that the pawls will not function to turn the spindle 86. For this purpose, the lever 262 is provided with a portion 266 extending at substantially a right angle to the arm 261 said portion being held in resilient engagement with a collar 267 fixed on the rod 221 by a spring 270 which is connected between the lever and a collar 281 also carried on the rod 221. Therefore, when the rod 221 is shifted toward the right (Fig. 32) by the lever 240 to shift the follower 127 by the lever 212 to maintain the follower positioned between the cams 131 and 132, as hereinbefore set forth, the lever 262 also shifts the follower 170 to maintain its position intermediate the cams 172 and 175.

The spindles 81 and 86 may also be turned in the counterclockwise or widening direction on a "down" stroke of the actuator members 105 and 150, respectively. For so turning the spindle 81 a pawl 271 is provided which adjustably carries a nose piece 272 adapted to engage the teeth of the ratchet wheel 206 (Fig. 9). The pawl 271 is pivotally mounted on the pin 100 in the lever 101 and is biased toward engagement with the ratchet wheel 206 by a spring 275 which is connected between the pawl and the member 99 (Fig. 14). For turning the spindle 86 in the widening direction on the "down" stroke of the actuator 150, a pawl 276 is provided having a nose piece 277 adjustably secured thereto (Fig. 11). The pawl 276 is pivoted on the pin 141, in the lever 142 and the nose piece 277 is biased toward engagement with the teeth of the ratchet wheel 257 by a spring 280 which is connected between the pawl 276 and the member 146 (Fig. 22). Means, constructed and operated as hereinafter set forth, controls the engagement of the pawls 271 and 276 with the ratchet wheels 206 and 257, respectively, to turn the spindles 81 and 86 and to hold the spindles in the positions to which they are moved by the pawls 207 and 256.

The cams 131 and 132 are of a height to move the actuator member 105 in both "up" and "down" strokes to move all of the pawls for the spindle 81 through a distance equal to one tooth of the ratchet wheels 96 and 206. The cams 172 and 175 are of a height to move

the actuator member 150 in both "up" and "down" strokes to move all of the pawls for the spindle 86 through a distance equal to three teeth of the ratchet wheels 140 and 257 for purposes hereinafter set forth.

The pawls for turning the spindles 81 and 86 in opposite directions for fashioning and resetting operations are individually controlled from the pattern chain device 199, the construction and operation of which is hereinafter set forth in detail.

For controlling the operation of the pawl 97, the pawl rotatably carries a roller type follower 282 which is adapted to engage high and low cam surfaces 285 and 286, respectively, of a control lever 287 pivotally mounted on a headed stud 290 carried in the bracket 91 for the spindle 81 (Figs. 9 and 17). The lever 287 rotatably carries a roller type follower 291 for engagement with a plate cam 292 pivotally mounted on the end of the spindle 81 adjacent to the ratchet wheel 96. The cam 292 is provided with a low portion 293, an intermediate portion 294 and a high portion 295 (Figs. 17 and 19) and the cam is rotated to selectively engage the different height portions with the roller 291. For rotating the cam 292, the cam is provided with a forked portion 296 for engagement with a pin 297 carried in one end of an adjustable link 298. The other end of the link 298 is pivotally connected to a pattern lever which is one of a group of similar levers 299, of the pattern chain device 199 pivotally carried on the shaft 198. Each of the levers 299 are provided with an adjustable bit 305 for engagement with buttons 306 on the chain 204 (Fig. 34) of the pattern chain device 199.

When no button is beneath the lever 299 connected to the cam 292, the rest position of the lever is determined by engagement of a portion 310 of the lever with one of the stop screws 229 carried in the bracket 218. In this position of the lever 299, the cam 292 is positioned with the low portion 293 thereof beneath the follower 291 which positions the lever 287 to permit engagement of the jawl 97 with the teeth of the ratchet wheel 96 (Fig. 10).

When the actuator member 105 is operated by the cam 131 to move the lever 101 clockwise, the pawl will advance the ratchet wheel 96 and spindle 81 a distance equal to one tooth of the ratchet wheel. When a low button 306 is beneath the lever 299, the cam 292 is turned to position the intermediate portion 294 beneath the follower 291. In this position the high cam surface 285 holds the pawl 97 above the teeth of the ratchet wheel 96 so that the pawl will miss the first tooth (Fig. 10) when the pawl is moved clockwise. As the pawl 97 is moved, the follower 282 rides from the high cam surface 285 on the lever 287 onto the low surface 286 which again permits engagement of the pawl with the next tooth without however turning the spindle 81. Engagement of the pawl 97 with the ratchet wheel 96 at this time acts to limit the movement of the spindle 81, to one tooth in the counterclockwise direction when operated by the pawl 207 as hereinafter set forth. When an intermediate height button 306 is beneath the lever 299, the cam 292 is turned to position the high portion 295 beneath the follower 291 which positions the lever 287 so that both surfaces 285 and 286 will hold the pawl 97 in a laid out position or out of engagement with the teeth of the ratchet wheel 96. Preferably, the intermediate height button 306 controls the position of the pawl 97 only during resetting of the spindle 81 by means other than the pawls as hereinafter set forth.

To control the operation of the pawl 207, the pawl carries a roller type follower 312 which is adapted to engage high and low cam surfaces 313 and 314, respectively, of a control lever 315 pivotally mounted on a pin 316 (Fig. 13). The pin 316 is carried in a bracket 317 supported from shafts 320 and 321 carried in suitable bearings in the brackets 91 and 92, respectively (Figs. 2 and 3). The lever 315 carries a roller type follower 322 for engagement with a plate cam 323 pivotally

mounted on the end of the spindle 81 adjacent to the ratchet wheel 206. The follower 322 is biased toward engagement with the cam 323 by a spring 318 which is connected between an arm 319 of the lever 315 and a pin 328 carried in the bracket 317 (Fig. 13). The plate cam 323 is provided with low, intermediate and high portions 324, 325 and 326, respectively (Figs. 13 and 15) and the plate cam is rotated to selectively engage the different height portions with the follower 322. For rotating the plate cam 323 the cam is provided with a forked portion 327 which engages a pin 330 in one end of an adjustable link 331 the other end of which is pivotally connected to one of the pattern levers 299. The lever 299 for the plate cam 323 has three operating positions corresponding to the three operating positions of the lever 299 for the plate cam 292. In the first position of the lever 299 in which it is in engagement with a stop screw 229, the low portion 324 of the plate cam 323 is in engagement with the follower 322 and the lever 315 is thereby positioned to permit the pawl to engage the teeth of the ratchet wheel 206. When the actuator 105 is operated by the cam 132, the lever 185 and the pawl 207 are turned counterclockwise to turn the spindle 81. When a low button 306 is beneath the lever 299 the intermediate portion 325 of the cam 323 is moved into engagement with the follower 322 to position the lever 315 as in Fig. 13. In this position the pawl 207 is held outside the periphery of the ratchet wheel 206 by the high surface 313 of the lever 315 and as the pawl is turned counterclockwise, the pawl will pass the first tooth of the ratchet wheel (Fig. 9). As the pawl 207 continues to move the follower 312 rides from the high surface 313 onto the low surface 314 which again permits the pawl to engage the next tooth of the ratchet wheel 206 without turning the spindle. Engagement of the pawl 207 with the ratchet wheel 206 at this time acts to limit the movement of the spindle 81 in the clockwise direction by the pawl 97 as hereinafter set forth. When an intermediate button 306 is beneath the lever 299, the high portion 326 of the cam 323 is moved to engage the follower 322 and the lever 315 is positioned to hold the pawl 207 in a laid out position or out of engagement with the ratchet wheel 206 during resetting movements of the spindle 81.

The operations of the pawls 180 and 271 are also controlled by plate cams rotatably carried on the end of the spindle 81. For controlling the pawl 180, the pawl carries a follower 332 which is adapted to engage high and low cam surfaces 333 and 334, respectively, of a lever 335 pivotally mounted on the pin 316 adjacent to the lever 315. The lever 335 carries a follower 336 for engagement with a plate cam 337 which is pivotally mounted on the end of the spindle 81. The cam 337 has low, intermediate and high portions 340, 341 and 342, respectively (Figs. 18 and 20), which are adapted to be selectively moved into position to engage the follower 336. The follower 336 is biased toward engagement with the cam 337 by a spring 343 which is connected between the lever 335 and the pin 328. For moving the plate cam 337 the cam is provided with a forked portion 345 which pivotally engages a pin 346 carried in one end of an adjustable link 347 having its other end pivoted to one of the pattern levers 299. The pattern lever 299 for the cam 337 has three operating positions similar to the operating positions of the levers 299 for the cams 292 and 323. When no button is beneath the lever 299 and it is supported on a stop screw 229, the low portion 340 is in engagement with the follower 336 on the lever 335. With the parts in this position the pawl 180 is in engagement with the ratchet wheel 96 and the follower 332 is held out of engagement with the low cam surface 334. As the pawl 180 is moved counterclockwise by the actuator member 105, the pawl rides over and engages the next adjacent tooth of the ratchet wheel 96 (Fig. 10), this being permitted although the

follower 332 is in engagement with the high cam surface 333 of the lever 335 at that time. As the actuator member 105 is returned to rest position the pawl 180 turns the ratchet wheel and spindle 81 a distance of one tooth of the ratchet wheel in the clockwise direction (Fig. 10).

When a low button 306 is beneath the lever 299, the intermediate portion 341 of the cam 337 is in engagement with the follower 336 and the lever 335 is positioned as in Figs. 18 and 20 with the follower 332 in engagement with the low cam surface 334 of the lever 335 and the pawl 180 in engagement with a tooth of the ratchet wheel 96 (Fig. 10). As the actuator member 105 moves upwardly, the follower 332 rides from the low cam surface 334 onto the high cam surface 333 of the lever 335 which raises and holds the nose piece 181 of the pawl 180 above the next tooth of the ratchet wheel 96 (Fig. 10). During the "down" movement of the actuator member 105 to its rest position nose piece 181 of pawl 180 passes a tooth of the ratchet wheel 96 without engagement and the follower again engages the low cam surface 334. The pawl 180 then comes to rest in engagement with a lower tooth of the ratchet wheel 96, as shown in Fig. 10, without turning the spindle 81. When a button 306 of intermediate height is beneath the lever 299, the high portion 342 engages the follower 336 which thereby positions the low cam surface 334 of the lever 335 to move the pawl 180 to laid out position or out of engagement with ratchet wheel 96, this being the position of the pawl during resetting movements of the spindle as hereinafter set forth.

To control the operation of the pawl 271, the pawl carries a follower 350 for engagement with high and low cam surfaces 351 and 352, respectively, of a lever 355 pivotally mounted on the pin 299. The lever 355 carries a follower 356 which is adapted to engage a plate cam 357 pivotally mounted on the end of the spindle 81. The plate cam 357 has low, intermediate and high portions 360, 361 and 362, respectively (Figs. 14 and 16), which are selectively moved into engagement with the follower 356 by rotating the plate cam on the spindle 81. For rotating the plate cam 357, the cam has a forked portion 365 which has pivotal engagement with a pin 366 carried in one end of an adjustable link 367. The other end of the link 367 is pivotally connected to one of the pattern levers 299. The lever 299 has three operating positions for rotating the plate cam 357 to engage the different height portions 360, 361 and 362 to operate the pawl 271 in a manner similar to the operation of the pawl 180.

The pawls 97, 180, 207 and 271 are also adapted to be moved to disengaged position with respect to their respective ratchet wheels when it is desired to manually turn the spindle 81. For this purpose a cam member 368 is provided for engaging and moving the pattern levers 299 connected to the plate cams 292, 323, 337, 357 to positions corresponding to the positions to which the pattern levers are moved by intermediate height buttons 306 as hereinbefore set forth. The cam member 368 is carried on a shaft 369 which also carries a handle 364 (Fig. 33). The cam member 368 is normally positioned as shown in Figs. 17 and 18 when the pattern levers are under the control of the pattern chain 294 and is manually rotated in a counterclockwise direction by means of the handle 364 to engage and raise the pattern levers whenever manual movement of the spindle 81 is desired.

It will be obvious from the foregoing that the separate control means for each of the pawls permits the pawls to act individually or in unison on the ratchet wheels to obtain the desired turning movement of the spindle 81. Also the control means permits the pawls not participating in a specific turning movement of the spindle 81 to act to prevent overtravel of the spindle during the turning movements and to lock the spindle against accidental turning movement such as otherwise might occur

when the carrier rods strike the end stops carried by the spindle. The control means also acts to prevent any action of the pawls on the spindle when means other than the pawls is acting to turn the spindle as herein-after set forth.

As an example of the functions of the various pawls associated with the spindle 81, when the spindle is to be turned to move the end stops 85 for the carrier rods in the narrowing direction no button 306 is provided on the chain for the lever 299 and the cam 292 and lever 287 are positioned as in Fig. 17. At this time a low button 306 is beneath each of the levers 299 for the cams 323, 337 and 357, respectively, which positions the lever 315, as shown in Fig. 13, to disengage the pawl 207 from the ratchet wheel 206 (Fig. 9), positions the lever 335 as shown in Fig. 18 to permit engagement of the pawl 180 with the ratchet wheel 96 (Fig. 10) and positions the lever 355, as shown in Fig. 14, to permit engagement of the pawl 271 with the ratchet wheel 206 (Fig. 9). When the camshaft 75 is shifted to institute a narrowing cycle, as hereinbefore set forth, the cam 131 operates the lever 122 to give the actuator member 105 an "up" movement to move the pawls 97 and 271 in the clockwise direction and the pawls 180 and 207 in the counterclockwise direction. During this action the pawl 97 turns the spindle 81 a distance of one tooth of the ratchet wheel 96 and the pawl 207 passes above the first tooth in its path of the ratchet wheel 206. As the follower 312 on the pawl 207 rides onto the low surface 314 of the lever 315 the pawl is again permitted to engage the ratchet wheel 206 and as the pawl 97 completes its movement the pawl 207 engages a tooth of the ratchet wheel 206 to stop further movement of the spindle 81. Also during this action, the pawls 180 and 271 are raised and held above the teeth of their associated ratchet wheels by the high portions of the levers 335 and 355, respectively. When the lever 122 and actuator member 105 are moved downwardly to rest position the pawls are returned to the positions shown in Figs. 9 and 10, in which positions the pawl 97 is in position to again advance the spindle 81 and the pawls 180 and 271 lock the spindle against movement in either direction. When the spindle 81 is to be turned in the counterclockwise or widening direction the action of the pawls 97 and 207 are reversed and the action of the pawls 180 and 271 are the same. Preferably the movement of the spindle in the counterclockwise direction is affected through the cam 132 during a knitting cycle.

At times it may be desirable to turn the spindle 81 a distance of two teeth of the ratchet wheels or four needles in either direction at each operation of the actuator member 105. To move the spindle 81 a distance equal to two teeth of the ratchet wheel 96 in the clockwise or narrowing direction, the pawls 97, 207 and 271 are again positioned as in Fig. 9 and 10 by their respective associated pattern levers 299 and the pawl 180 is also positioned as in Fig. 10. However, at this time there is no button beneath the lever 299 controlling the cam 337 which positions the low portion 340 in engagement with the follower 336 to thereby move the low surface 334 of the lever 335 out of engagement with the follower 332 on the pawl 180. When a movement of the actuator member 105 is instituted, as hereinbefore set forth, the pawl 97 turns the spindle 81 one tooth of the ratchet wheel 96 and the pawl 207 acts to stop the movement of the spindle on the "up" movement of the actuator. At this time the pawl 180 remains in engagement with the ratchet wheel 96 and the pawl 271 is disengaged from the ratchet wheel 206. As the actuator member 105 is returned to its rest position the pawl 180 turns the spindle 81 an additional distance of one tooth and all of the pawls again return to their positions of Figs. 9 and 10. The spindle 81 is moved a distance of two teeth of the ratchet wheel 206 in the counterclockwise or widening direction by reversing the action of the pawls 97, 180 and 207, 271.

As heretofore set forth, the spindle 81 is moved in the clockwise direction by the cam 131 during a narrowing cycle and the spindle is moved in the counterclockwise direction by the cam 132 during a knitting cycle. However, the arrangement of the parts is such that the movement of the spindle in both the clockwise and counterclockwise direction may be made with either the cam 131 or 132 and hence in either a narrowing or a knitting cycle. Referring now to the control of the pawls for spindle 86, the pawl 137 carries a follower 370 for engagement with different height cam surfaces 371, 372, 373 and 374 of a lever 375 (Fig. 27) pivotally mounted on a pin 376 carried in the bracket 317 (Fig. 21). The lever 375 carries a follower 377 for engagement with a plate cam 380 (Figs. 25 and 27) pivotally mounted on the end of the spindle 86 adjacent to the ratchet wheel 140. The follower 377 is biased toward the plate cam 380 by a spring 381 which is connected between an arm 382 of the lever 375 and a pin 385 in the bracket 317. The plate cam 380 is provided with different height portions 386, 387, 388, 389 and 390 (Fig. 27) and the cam is rotated to selectively engage the different height portions with the follower 377. For rotating the plate cam 380, the plate cam is provided with a forked portion 391 which has a pivotal connection with a pin 392 carried in one end of an adjustable link 395. The link 395 is pivotally connected to one of a group of similar pattern levers 396 which are pivotally carried on the shaft 198 of the pattern chain device 199. Each of the levers 396 is provided with an adjustable bit 397 for engaging buttons 306 on the chain 204.

When a low button 306 is in engagement with the lever 396 connected to the plate cam 380, the plate cam is positioned to engage the portion 387 thereof with the follower 377 (Fig. 27). In this position the lever 375 is positioned, as shown in Fig. 27, with the follower 370 in engagement with the cam surface 371 to hold the pawl 137 out of engagement with the teeth of the ratchet wheel 140 (Fig. 12). When the actuator member 150 is operated in an "up" stroke by the cam 172 during a narrowing cycle, to move the lever 142 and the pawl 137 clockwise, the pawl will pass above the first tooth of the ratchet wheel 140 and as the follower 370 rides from the cam surface 371 to the cam surface 372 the pawl will drop into engagement with the second tooth of the ratchet wheel from its position of Fig. 12. Therefore, as the actuator 150 continues to the end of its "up" stroke, the pawl 137 will turn the ratchet wheel 140 and spindle 86 a distance equal to two teeth of the ratchet wheel.

When a button 306 of intermediate height is beneath the lever 396 for the plate cam 380, the portion 388 of the plate cam is engaged with the follower 377 to position the lever 375 to hold the pawl 137 out of engagement with the ratchet wheel 140. With the parts in this position and when the actuator 150 is operated to move the pawl 137 clockwise, both cam surfaces 371 and 372 will cause the pawl to pass above two teeth of the ratchet wheel 140 and as the follower 370 rides from the surface 372 to the surface 373, the pawl will drop into engagement with the third tooth of the ratchet wheel. As the actuator 150 continues to the end of its stroke the pawl 137 will turn the spindle 86 a distance equal to one tooth of the ratchet wheel 140. When a high button 306 is beneath the lever 396, the portion 389 of plate cam 380 is engaged with the follower 377 and the cam surfaces 371, 372 and 373 of the lever 375 are positioned to hold the pawl 137 above three teeth of the ratchet wheel 140 as the pawl is moved clockwise by the actuator 150. As the actuator continues to the end of its stroke, the follower 370 rides from the cam surface 373 to the cam surface 374 which permits the pawl 137 to drop into engagement with the ratchet wheel 140 and come to rest against the fourth tooth of the ratchet wheel from its position in Fig. 12. When the lever 396 for the plate cam 380 is against one of the stop screws 229, the portion 386 of

the plate cam is in engagement with the follower 377 which positions the surface 371 to permit engagement of the pawl 137 with the first tooth of the ratchet wheel 140. Therefore, as the pawl 137 is moved by the actuator the ratchet wheel 140 and spindle 86 are moved a distance of three teeth of the ratchet wheel.

To control the operation of the pawl 256, the pawl is provided with a follower 400 which is adapted to engage cam surfaces 401, 402, 403 and 404 of a control lever 405 (Fig. 23) pivotally mounted on a pin 406 carried in the bracket 92 (Fig. 21). The lever 405 carries a roller type follower 407 for engagement with a plate cam 410 pivotally mounted on the end of the spindle 86. The plate cam 410 is provided with different height portions 411, 412, 413, 414 and 415 and is rotated to selectively engage the different height portions with the follower 407. To rotate the plate cam 410 the cam is provided with a forked portion 416 which pivotally engages a pin 417 carried in one end of an adjustable link 420 the other end of which is pivotally connected to one of the pattern levers 396.

When a high button 306 is beneath the lever 396 for the plate cam 410, the portion 414 of the plate cam is in engagement with the follower 407 as shown in Fig. 23. In this position with the follower 400 in engagement with the cam surface 401, the lever 405 positions the follower to hold the pawl 256 out of engagement with the teeth of the ratchet wheel 257, as shown in Figs. 11, 21 and 23. When the actuator 150 is operated in an "up" stroke by the cam 172, during a narrowing cycle, to move the lever 197 and pawl 256 counterclockwise, the pawl will be held in positions by cam surfaces 401, 402 and 403 to pass above the teeth of the ratchet wheel 257. Then as the actuator continues to the end of its stroke, the follower 400 rides from the cam surface 403 to the cam surface 404 which permits the pawl 256 to engage the ratchet wheel 257 and come to rest against the fourth tooth without however moving the ratchet wheel and spindle 86. When an intermediate or low button 306 is beneath the lever 396 or the lever is in engagement with its stop screw 229, the plate cam 410 and lever 405 are positioned to permit the pawl 256 to turn the ratchet wheel 257 distances of one, two or three teeth, respectively, in the counterclockwise direction in the same manner that the ratchet wheel 140 is turned in the clockwise direction by the pawl 137, as hereinbefore set forth.

The operation of the pawls 192 and 276 are also controlled by plate cams pivotally carried on the end of the spindle 86. For controlling the pawl 192, the pawl is provided with a follower 421 which is adapted to engage cam surfaces 422, 423, 424 and 425, respectively, on a control lever 426 (Figs. 26 and 28) pivotally mounted on the pin 406. The lever 426 carries a follower 427 for engagement with a plate cam 430 rotatably carried on the end of the spindle 86. The plate cam 430 has different height portions 431, 432, 433, 434 and 435 and is rotated to selectively engage the different height portions with the follower 427. To rotate the plate cam 430 the plate cam is provided with a forked portion 436 which is in pivotal engagement with a pin 437 carried in one end of an adjustable link 440. The other end of the link 440 is pivotally connected to one of the pattern levers 396 of the pattern device 199.

When a high button 306 is beneath the pattern lever 396 for the plate cam 430, the surface 434 of the plate cam is in engagement with the follower 427 which positions the lever 426 as in Figs. 26 and 28 and the pawl 192 is in engagement with the ratchet wheel 140 as shown in Fig. 12. When the actuator 150 is operated in an "up" stroke by the cam 172 during a narrowing cycle, to move the lever 197 and pawl 192 in a counterclockwise direction, as the follower 421 rides from the cam surface 422 to the cam surface 423 the pawl is disengaged from the ratchet wheel 140. As the pawl 192 continues to the end of its movement, the follower 421 successively

engages the cam surfaces 424 and 425 to maintain the pawl disengaged from the teeth of the ratchet wheel 140. Upon movement of the actuator 150 to rest position the follower 421 again engages the cam surface 422 on the lever 426 and the pawl 192 comes to rest against a tooth of the ratchet wheel 140 without, however, moving the ratchet wheel and spindle 86.

When a button 306 of intermediate height is beneath the pattern lever 396 the portion 433 of the plate cam 430 is in engagement with the follower 427 to position the lever 426. In this position of the lever 426, the cam surface 423 also permits engagement of the pawl 192 with the teeth of the ratchet wheel 140. Therefore, as the actuator 150 is returned to rest position the pawl 192 will engage the ratchet wheel 140 when the follower engages the cam surface 423 and turn the ratchet wheel and spindle 86 a distance of one tooth in the clockwise direction. A low button 306 beneath the pattern lever 396 will move the portion 432 of the plate cam into engagement with the follower 427. In this position the cam surface 424 of the lever 426 permits engagement of the pawl 192 with the ratchet wheel 140 to turn the ratchet wheel and spindle 86 a distance equal to two teeth of the ratchet wheel in the clockwise direction. When the pattern lever 396 rests on the stop screw 229, the lever 426 is positioned by the portion 431 of the cam plate 430 so that cam surface 425 will also permit engagement of the pawl 192 with the ratchet wheel 140. Therefore, as the actuator 150 is returned to rest position, the pawl 192 turns the ratchet wheel 140 and spindle 86 a distance equal to three teeth in the clockwise direction.

To control the operation of the pawl 276 the pawl is provided with a follower 441 which is adapted to engage cam surfaces 442, 443, 444 and 445 of a control lever 446 (Figs. 22 and 24) pivotally mounted on the pin 376. The lever 446 carries a follower 447 which is biased into engagement with a plate cam 450 pivotally mounted on the end of the spindle 86, by a spring 448 which is connected between the bracket 317 and a tail portion 449 of the lever (Fig. 22). The plate cam 450 is provided with different height portions 451, 452, 453, 454 and 455 and is rotated to selectively engage the different height portions with the follower 447. To rotate the plate cam 450 it is provided with a forked portion 456 which pivotally engages a pin 457 in an adjustable link 460 pivotally connected to one of the pattern levers 396 (Fig. 22).

When a high button 306 is beneath the lever 396 for the plate cam 450 the portion 454 of the plate cam is in engagement with the follower 447 and the lever 446 is positioned as shown in Fig. 24. In this position of the lever 446 with the follower 441 in engagement with the cam surface 442 of the lever, the pawl 276 is in engagement with the ratchet wheel 257 as shown in Fig. 11. During an "up" stroke of the actuator 150 to move the lever 142 and pawl 276 in the clockwise direction, the follower 441 rides from the cam surface 442 to the cam surface 443 to disengage the pawl from the ratchet wheel 257. As the pawl 276 continues to the end of its movement, the follower 441 successively engages the portions 444 and 445 on the lever 446 to maintain the pawl disengaged from the ratchet wheel 257. During the "down" movement of the actuator 150 to rest position, the follower 441 comes to rest on the portion 442 of the lever 446 and the pawl 276 drops into engagement with the ratchet wheel 257 and comes to rest against the tooth of the ratchet wheel as shown in Fig. 11 without however turning the spindle 86. When an intermediate or low button 306 is in engagement with the pattern lever 396 or the lever is in engagement with its setscrew 229, the plate cam 450 and lever 446 are positioned to permit the pawl 276 to engage and turn the ratchet wheel 257 and spindle 86 distances equal to one, two or three teeth of the ratchet wheel, respectively, in the counterclockwise direction in the same manner that the ratchet wheel 140

is turned in the clockwise direction by the pawl 192, as hereinbefore set forth.

From the foregoing it will be seen that the separate control means for each of the pawls permits the pawls to act individually or in unison on the ratchet wheels to turn the spindle 86 in either direction as desired. The control means also permits the pawls not acting in a particular turning movement of the spindle 86 to cooperate with their respective ratchet wheels to prevent overtravel of the spindle during the turning movements and to maintain the spindle in fixed positions between turning movements. The control means also acts to prevent any action of the pawls on the spindle when the spindle is turned by means other than the pawls as hereinafter set forth.

The pawls 137, 192, 256 and 276 are also adapted to be disengaged from their respective ratchet wheels when it is desired to manually turn the spindle 86. For this purpose, the cam member 368 is also adapted to raise the pattern levers 396 connected to the plate cams 380, 430, 410 and 450, respectively, to rotate the plate cams and position the portions 390, 435, 415 and 455 thereof in engagement with the control levers 375, 426, 405 and 446, respectively. The cam member 368 is normally positioned with respect to the pattern levers 396, as shown in Fig. 25, when the pattern levers are under the control of the pattern chain 204 and is manually rotated in a counterclockwise direction to engage and raise the pattern levers as previously described.

As an example of the operations of the various pawls associated with the spindle 86, when the spindle is to be turned to move the nuts 90, for the point comb rods 89, a distance equal to two needles in the narrowing direction, a low button 306 on the pattern chain 204 is beneath the pattern lever 396 to position the plate cam 380 and control lever 375 as shown in Figs. 25 and 27 and the pawl 137 is positioned as in Fig. 12. At this time a high button 306 is beneath each of the levers 396 for the plate cams 410, 430 and 450, respectively, which positions the lever 405 (Fig. 23) to disengage the pawl 256 from the ratchet wheel 257 (Fig. 11), positions the lever 426 as shown in Fig. 28 to permit engagement of the pawl 192 with the ratchet wheel 140 (Fig. 12) and positions the lever 446, as shown in Fig. 24 to permit engagement of the pawl 276 with the ratchet wheel 257 (Fig. 11). When the camshaft 75 is shifted to its narrowing position, the cam 172 operates the lever 166 to give the actuator 150 an "up" movement to move the pawls 137 and 276 in the clockwise direction and the pawls 256 and 192 in the counterclockwise direction (Figs. 11 and 12). During this movement the lever 375 holds the pawl 137 in position to pass above the first tooth of the ratchet wheel 140 and permits the pawl to engage the second tooth and then turn the ratchet wheel and spindle 86 a distance equal to two teeth in the clockwise direction. Also during this movement, the pawl 256 will be held in position to pass three teeth of the ratchet wheel 257 and the pawls 192 and 276 will be raised and held above the teeth of their associated ratchet wheels by the levers 426 and 446, respectively. As the follower 400 on the pawl 256 rides onto the cam surface 404 (Fig. 23) the pawl again engages the ratchet wheel 257 and comes to rest against the fourth tooth of the ratchet wheel, from its position in Fig. 11, to stop further movement of the spindle 86 in the clockwise direction by the pawl 137.

When the lever 166 and actuator member 150 are moved in a "down" stroke to rest position the pawls are returned to the positions of Figs. 11 and 12, in which the pawl 137 is in position to again turn the spindle 86 and the pawls 192 and 276 lock the spindle against movement in either direction.

When the spindle 86 is to be turned in the counterclockwise direction the pawl 256 is controlled to turn the spindle, the pawl 137 acts to stop overtravel of the

spindle and the action of the pawls 192 and 276 are as described above.

In the usual practise the spindle 86 is turned a distance of two teeth of the ratchet wheel 140 in the clockwise direction by means of the pawl 137 to thereby move the point combs a distance equal to two needle spaces to form so-called two needle narrowings. In some instances, however, it may be desirable to control the pawl 137 to turn the spindle 86 a one tooth distance to move the point combs to form one needle narrowings in the fabrics. Preferably to widen the fabrics by means of the point combs, the pawl 256 is controlled and operated to turn the spindle 86 only a distance of one tooth of the ratchet wheel 257 in the counterclockwise direction. The pawls 192 and 276 may also be controlled and operated to cooperate with the pawls 137 and 256 to turn the spindle 86 to idly move the point combs one, two or three needle spaces in the narrowing or widening direction on the down stroke of the actuator 150 after narrowing or widening operations to reset the point combs for a subsequent fashioning operation. All movements of spindle 86 to fashion the fabrics and to reset the point combs coincident with fashioning operations are made under the control of the cam 172 when the camshaft 75 is shifted to the right, which is the narrowing position of the camshaft as hereinbefore set forth.

The pawls for the spindle 86 are also controlled and operated to turn the spindle in either direction to reset the point combs during the knitting operations between fashioned portions of the stocking fabrics and to reset the combs to starting position at the completion of the stocking fabrics. For this purpose the follower 170 on the lever 166 is shifted into alignment with the cam 175 by a button on the pattern chain device 199 while the camshaft 75 remains in its knitting position as hereinbefore set forth. The pawls 137 and 192 are controlled so that the pawl 137 is operated on the "up" stroke of the actuator 150 to turn the spindle 86 a distance equal to one, two or three teeth of the ratchet wheel 140 in the clockwise direction and the pawl 192 is operated on the "down" stroke of the actuator to turn the spindle an additional distance of one, two or three teeth of the ratchet wheel in the same direction. Likewise, the pawls 256 and 276 are adapted to turn the spindle 86 distances equal to one, two or three teeth of the ratchet wheel 257 in the counterclockwise direction on the "up" and "down" strokes, respectively, of the actuator 150. During the turning movements of the spindle 86 either in the clockwise or counterclockwise direction by the pawls 137, 192 or 256, 276, the pawls not participating in the turning movement will act to prevent overtravel of the spindle by the pawls effecting the turning movement as previously set forth. With this arrangement the pawls are manipulated to turn the spindle 86 distances of one to six teeth of the ratchet wheels in either direction during each operation of the actuator member 150 in knitting cycles of the machine whereby the point combs may be rapidly repositioned during the knitting interval between the various fashioned portions of the stocking fabrics.

The spindles 81 and 86 are also provided with discs 461 and 462, respectively, having V-shaped notches in the periphery thereof, the notches in the disc 461 having a spacing corresponding to the teeth in the ratchet wheels 96 and 206 and the notches in the disc 462 having a spacing corresponding to the teeth in the ratchet wheels 140 and 257 (Figs. 9 and 11). The notches in the discs 461 and 462 are engaged by correspondingly shaped ends of usual spring pressed detents 463 and 464, respectively, to facilitate centering and maintaining the spindles 81 and 86 in the exact angular position to which the spindles are moved by their respective pawls. The detents 463 and 464 may be disengaged from the notches in the discs 461 and 462 in the usual manner by levers 465 and 466, respectively, when it is desired to manually turn the spindles 81 and 86 to adjust the spindle mechanism. For

this purpose the spindles 81 and 86 are provided with usual handles 467 and 468, respectively (Fig. 1). Also at this time all of the pawls for the spindles are disengaged from their respective ratchet wheels by the cam member 368 as hereinbefore set forth.

As hereinbefore set forth, the operations of the various pawls acting on the spindles 81 and 86 are controlled by pattern levers which are actuated by buttons 306 on the chain 204 of the pattern chain device 199. The chain 204 is carried on a toothed sprocket drum 471 rotatably mounted on a shaft 472 (Fig. 34) and is directed over a series of idler rollers 475 (Fig. 33) rotatably carried on the framework of the machine. The shaft 472 is carried in the bracket 157 which is fixed to the end frame 60 as previously set forth, the bracket member also supporting one end of the shaft 198 on which the pattern levers for the pawls are pivotally mounted. The end of the sprocket 471 is rotatably supported in a stiffening member 480 which is carried on the shaft 198 and a supporting shaft 481 one end of which is carried in the bracket 157, as shown in Figs. 33 and 34. The shaft 369 for the cam 368 is also supported for rotation in the bracket 157 and member 480. The sprocket wheel 471 is provided with a toothed portion 482 which is adapted to be engaged by a pawl 485 pivotally carried on a lever 486 pivoted on the shaft 472. A spring 487 connected between the pawl 485 and lever 486 holds the pawl in engagement with the toothed portion 482 (Fig. 35). The lever 486 and pawl 485 are actuated to turn the sprocket drum 471 to advance the chain 204 by a link 490 one end of which is pivotally connected to the lever 486 (Fig. 36). The other end of the link 490 is pivotally connected to an arm 491 secured to a shaft 492 which is pivotally carried in brackets 495 and 496 secured to the end frame 60 and the center bed 66, respectively, of the machine, as shown in Figs. 30 and 33.

The shaft 492 carries a second arm 497 which is connected by a link 500 to one end of a lever 501 pivoted in a bracket 502 carried on the back beam 65. The lever 501 carries a follower 505 which is biased toward engagement with a cam 506, on the camshaft 75, by a spring 507 connected between the lever and a fixed part of the machine. Normally the lever 501 is supported by a lever 510 to hold the follower 505 in the position of Fig. 30 to which it is moved by the high part of the cam 506. The lever 510 is pivotally mounted on a bracket 511 fixed on the front beam 62 and is resiliently connected by means of a spring 515 to a rod 516 operated by one of the pattern levers 253 of the pattern chain mechanism 70. When the pawl 485 is to be moved to turn the drum 471 a distance of one tooth of the portion 482 to advance the chain one link, a button on the pattern chain mechanism 70 actuates the lever 253 to shift the rod 516 to the left, as viewed in Fig. 29, to remove the lever 510 from beneath the end of the lever 501. As the follower 505 follows the outline of the cam 506 the links 500 and 490 and the lever 486 are operated to move the pawl 485 to advance the drum 471 and chain 204. Rotative movement of the sprocket drum 471 to advance the chain 204 is retarded by a friction disc 517 which is pressed against the end of the drum by springs 520 carried in a nut 521. The nut 521 is adjustably carried in the member 480 to vary the pressure of the disc 517 against the drum 471. A detent 522, pivoted on the shaft 198, is provided to engage the toothed portion 482 of the drum 471 to prevent accidental rearward displacement of the drum when the pawl 485 is returned to its position of Fig. 35 for engagement with another tooth of the portion 482. The detent 522 is held in resilient contact with the toothed portion 482 by engagement of a spring pressed pin 523 with a flat surface 524 formed on the shaft 198.

At the completion of a set of stocking blanks it is desir-

able to rapidly reset the spindle 81 and the nut 82 to starting position. According to the invention the means for this purpose includes a commercial type combined motor and gear reduction unit 525 which is carried on a bracket 526 secured to the back beam 65, as shown in Figs. 37 and 39. A shaft 527 of the unit 525 carries a sprocket wheel 530 which is connected by a chain 531 to a sprocket wheel 532 fixed to the end of the spindle 81 remote from the end carrying the ratchet wheels 96 and 206. The chain 531, which is partially shown in dot-and-dash outline in Fig. 37, is guided between the sprocket wheels 530 and 532 by idler rolls 535 rotatably carried on fixed parts of the machine. The sprocket wheel 530 is normally free running on the shaft 527 and is turned relative to the shaft 527 as the spindle 81 is rotated during fashioning operations. The sprocket 530 is adapted to be connected to the shaft 527 by means of a friction clutch 536 of the floating disc type which is not shown in detail herein but which is of a type readily procurable commercially. The clutch 536 is keyed to the shaft 527 to rotate therewith and is also shiftable on the shaft to connect the sprocket wheel 530 to and disconnect it from the shaft.

For shifting the clutch 536 on the shaft, the clutch 25 is grooved as at 537 for the reception of shoes 540 pivotally carried in arms 541 and 542, respectively, of a forked shifting lever 545, as shown in Figs. 37 and 40. The lever 545 is pivotally mounted on a shaft 546 carried in a bracket 547 secured to the bracket 526. The arm 542 of the lever 545 extends beyond the shoes 540 and is connected by means of an adjustable link 550 to a core member 551 of a pull-type solenoid 552. The solenoid 552 is carried in a housing 555 secured to a fixed part of the framework of the machine (Figs. 38 and 39). The motor and gear reduction unit 525 and the solenoid 552 are in an electrical circuit which when energized to start the unit also causes the core member 551 of the solenoid to move the lever 545 and clutch 536 to the left as viewed in Fig. 39. Movement of the clutch 536 to the left frictionally connects the sprocket wheel 530 to the shaft 527 to thereby operate the chain 531 and turn the spindle 81 in the counterclockwise direction to reset the nut 82 to starting position.

The electrical circuit for the unit 525 and solenoid 45 552, diagrammatically shown in Fig. 39, includes main conductors 675 and 676 connected to the main electrical source, a conductor 677 connected to the conductor 675 and passing through stationary contact members 678 of a relay switch 679 to the unit, and a conductor 680 connecting the unit to the conductor 676. The solenoid 552 is connected to the conductors 677 and 680 by conductors 681 and 682, respectively. The switch 679 includes a contact member 683 connected to a core member 684 which is adapted to be operated by a solenoid 552 winding or coil 685 to draw the member 683 into engagement with the contact members 678 to close the circuit through the unit 525. The coil 685 is in a holding circuit including a conductor 686 connecting the main conductor 676 and passing through the coil to a normally closed limit switch 687. From the limit switch 687 the circuit continues through a switch 688 to the main conductor 675. The switch 688 is of the push button type that is automatically opened when the circuit, in which it is connected, is opened at the limit switch 687, as hereinafter set forth.

When the circuit through the unit 525 is to be closed and the unit operated to reset the spindle 81, the push button switch 688 is closed to energize the winding 685 to draw the member 683 into engagement with the members 678 to close the switch 679. Closing the switch 679 also energizes and operates the solenoid 552 to operate the clutch 536 to connect the sprocket wheel 530 to the shaft 527 and drive the spindle 81.

When the resetting movement of the nut 82 is completed 75 the electrical circuit for the unit 525 is again opened to

stop the unit and to deenergize the solenoid 552 to disengage the clutch 536 from the sprocket wheel 530. For this purpose the limit switch 687 is opened to deenergize the circuit through the winding 685 which causes the switch 688 to open and permits disengagement of the contact member 683 from the contact members 678 by a spring 689.

For opening the limit switch 687 it is provided with a push button 557 which is adapted to be contacted by a rod 560 (Fig. 42) mounted on a sleeve 561 slidably mounted on a shaft 562 carried in bearings fixed on the framework of the machine one of which is shown at 563 in Fig. 41. The sleeve 561 is secured to a bracket 565 (Figs. 41 and 43) which is slidably journaled on the shaft 320 carried in the brackets 91 for the spindle 81. The bracket 565 is secured to a portion 564 of the nut 82. As the nut 82 reaches the end of its resetting movement, the rod 560 depresses the button 557 to open the limit switch 687 thereby breaking the circuit through the starting switch to stop the unit 525.

During resetting of the spindle 81 the detent 463 is disengaged from the notched disc 461 to avoid friction between the parts and noise resulting from a rapid engagement and disengagement of the detent with the notches. To disengage the detent 463, the detent carries a pin 567, extending at right angles to the axis of and beyond opposite sides of the detent as shown in Figs. 9 and 41. The detent 463 is raised to disengage it from the disc 461 by fingers 570 which are adapted to engage the portions of the pin 567 extending from opposite sides of the detent 463. The fingers 570 are carried on a shaft 571 one end of which is pivotally journaled in the bracket 91 (Figs. 3 and 9). The other end of the shaft 571 is pivotally carried in a bracket 572 fixed on the end frame 60 as shown in Fig. 41. The shaft 571 carries a lever 575 the free end of which is connected to a core member 576 of a solenoid 577 secured to the machine framework (Figs. 41 and 42). The solenoid 577 is connected to the conductors 677 and 682 (Fig. 39) of the electrical circuit for the unit 525 and solenoid 552 and is simultaneously energized therewith to move the lever 575 and shaft 571 in the counterclockwise direction and thereby disengage the detent 463 from the disc 461. When the resetting of the spindle 81 is completed and the electrical circuit deenergized by the limit switch 687, as hereinbefore set forth, the detent 463 is returned to engagement with the disc 461.

Rotative movement of the spindle 81 in the counterclockwise direction by the pawl 207 and/or the pawl 271, as hereinbefore set forth, is controlled to prevent accidental overtravel of the nut 82 on the spindle beyond predetermined limits. The means for this purpose includes a cam member 580 fixed on the bracket 565 (Figs. 41 and 43) for movement with the nut 82. The high face 579 of the cam member 580 normally lies beyond the plane of a high cam surface 581 of a block 582 which is adjustably secured to a bridge member 585 mounted on levers, one of which is shown at 586 (Figs. 41 and 43). The levers 586 are secured to the shaft 320 carried in the brackets 91 and are provided with adjustable studs 587 which are adapted to engage the base plate 95 to limit the movement of the lever and shaft in a counterclockwise direction. A spring 590 connected between the lever 586 and the brackets 317 (Fig. 1) serves normally to resiliently hold the stud 587 in contact with the base plate 95.

Also secured to the shaft 320, at the end thereof, is a member 591 provided with an arm 592 having a rod 595 pivotally connected thereto. The rod 595 extends through the arm 319 of the control lever 315 for the pawl 207 and adjustably carries a collar 597 for engagement with a curved face 598 of the arm, as shown in Fig. 13. The member 591 has a second arm 600 having a rod 601 pivotally connected thereto. The rod 601 extends through a tail portion 602 of the control lever 355

for the pawl 271 and carries a collar 605 for engagement with the curved face 606 of the tail portion, as shown in Fig. 14. Normally the high faces 579 and 581 lie adjacent to each other, as viewed in Fig. 43, when the nut 82 has reached the limit of its movement to the right, as viewed in Fig. 3, through the action of the pawl 207 and/or pawl 271 on the spindle 81. When, however, the pawls 207 or 271 continue to rotate the spindle 81, due to the failure or improper setting of the pattern mechanism 199, the high face 579 of the cam member 580 engages the high face 581 of the block 582 thereby turning the lever 586 and shaft 320 clockwise, as viewed in Fig. 41. Clockwise movement of the shaft 320 also turns the member 591 clockwise to pull the control lever 315 clockwise and disengage the pawl 207 from its ratchet wheel 206 and to also push the control lever 355 to disengage the pawl 271 from the ratchet wheel, as viewed in Figs. 13 and 14, respectively. Further counterclockwise rotation of the spindle 81 by the pawls 207 and 271 is thereby prevented until the cam 580 is moved to the left as viewed in Fig. 43, to again disengage the surface 579 from the high portion 581 of the block 582. This correction would be made manually.

The rotative movement of the spindle 86 in the clockwise and counterclockwise directions is controlled to prevent movements of the nuts 90 and the point comb rods 89 beyond predetermined limits toward and away from each other. For preventing excessive movement of the nuts 90 toward each other, when the spindle 86 is rotated clockwise by the pawl 137 and/or the pawl 192, the nut shown in Fig. 44, which is the left one of the nuts on the spindle 86, is adapted to engage a collar 610 fixed on a rod 611 slidably carried in the brackets 92 for the spindle (Figs. 44 and 46). The rod 611 is biased to the left, as viewed in Fig. 46, by a compression spring 609 which is carried on the rod between the right bracket 92 and a collar 613 fixed on the rod. Movement of the rod 611 to the left is limited by engagement of a collar 614 with the left bracket 92. The end of the rod 611 is normally positioned to support an arm 612 of a member 615 pivotally journaled on the shaft 321, the arm being biased toward the rod 611 by a spring 616 connected to the member and the bracket 92 (Figs. 45 and 46). The member 615 is pivotally connected to a link 617 which extends through the arm 382 of the control lever 375 for the pawl 137 and carries a collar 620 for engagement with a curved surface 621 of the arm as shown in Fig. 25. A link 622 also pivotally connected to the member 615 extends through an arm 625 of the control lever 426 and carries a collar 626 for engagement with a curved surface 627 of the arm. The collar 626 is maintained in contact with the surface 627 by a spring 630 which is carried on the link 622 and compressed between the arm 625 and a second collar 631 fixed on the end of the link as shown in Fig. 26.

As hereinbefore set forth, the arm 612 is normally supported by the rod 611 as shown in Fig. 46 which permits either or both of pawls 137 and 192 to turn the spindle 86 in the clockwise direction under the control of the pattern chain device 199. During fashioning operations of the point combs to narrow the stocking fabrics the spindle 86 is turned by the pawls 137 or 192 to move the left nut 90 to a position closely adjacent to the collar 610. When either of the pawls inadvertently continues to operate, the left nut 90 engages and pushes the collar 610 and rod 611 to the right, as viewed in Fig. 44, to remove the end of the rod from beneath the arm 612. As the rod 611 moves from beneath the arm 612 the spring 616 turns the member 615 counterclockwise to engage a cut-out portion 632 of the arm 612 with the rod. Counterclockwise movement of the member 615 pulls the control lever 375 to turn it counterclockwise to disengage the pawl 137 from the ratchet wheel 140 and pushes the control lever 426 counterclockwise to disengage the pawl 192 from the ratchet wheel. Pawls 137 and 192 will

remain in disengaged position until the spindle 86 is rotated counterclockwise to move the nut 90 to the left (Fig. 44) and disengage it from the collar 610. This operation is manually performed.

To prevent movement of the nuts 90 away from each other or the left nut to the left, as viewed in Fig. 44, beyond predetermined limits, the left nut carries a contact member 635 which is adapted to engage an adjustable end 636 of a rod 637 slidably mounted in a portion 640 of the left bracket 92 and an arm 641 of the bracket 317. The rod 637 is biased to the right, as viewed in Fig. 44 by a spring 642 carried on the rod between the arm 641 and a collar 645 on the rod. The rod 637 is prevented from turning in the portion 640 and arm 641 by a member 646 secured on the rod and having a forked end 647 embracing a pin 650 (Figs. 44 and 45) carried in the portion 640. The member 646 engages the portion 640 of the bracket 92 to also limit movement of the rod 637 to the right (Fig. 44). The rod 637 is provided with a bevelled surface 651 joining the peripheral surface of the rod and a flat 652 formed on the end of the rod (Fig. 48). The flat 652 of the rod 637 is adapted to be engaged by a finger 653 of a lever 655 pivotally carried on a pin 656 fixed in the arm 641 (Fig. 47). The lever 655 has an arm 657 pivotally connected to a link 660 which extends through a tail portion 661 of the control lever 405 for the pawl 656, the link having a collar 662 fixed thereto for engagement with a curved surface 665 on the tail portion (Fig. 21). The lever 655 has a second arm 666 pivotally connected to a link 667 which extends through the tail portion 449 of the control lever 446 for the pawl 276, the link having a collar 670 for engagement with a curved surface 671 on the tail portion (Fig. 22).

During operations of the pawls 256 and 276 to reset the nuts 90 and point combs outwardly to starting position, as hereinbefore set forth, the finger 653 is biased into engagement with the flat 652 on the rod 637 by a spring 672 which is connected between the arm 641 of the bracket 317 and the arm 657 of the lever 655 (Fig. 2). When, for any reason, the pawls inadvertently continue to operate to move the nuts 90 beyond their outward limit, the member 635 engages and moves the rod 637 to the left, as viewed in Fig. 44. Leftward movement of the rod 637 causes the bevelled surface 651 to engage and turn the finger 653 and lever 655 counterclockwise (Fig. 22). Counterclockwise movement of the lever 655 moves the rods 660 and 667 to turn the control levers 405 and 446 counterclockwise to positions corresponding to the positions to which the levers are moved by the high portions of the plate cams 410 and 450, respectively, as hereinbefore set forth. In these positions of the levers 405 and 446, the pawls 256 and 276 are prevented from engaging the ratchet wheel 257 regardless of the positions of cams 410 and 450 to thereby prevent further rotation of the spindle 86 by the pawls. The pawls 256 and 276 will remain disengaged from the ratchet wheel 257 until the spindle 86 is manually turned clockwise to disengage the member 635 from the rod 637 and the spring 642 moves the rod to the right to its position as viewed in Figs. 44 and 48. As the rod 637 is moved to the right, the finger 653 is biased by spring 672 into engagement with the flat 652 on the rod which turns the lever 655 clockwise to permit the levers 405 and 446 to return to engagement with the plate cams 410 and 450, respectively.

From the foregoing description the manner of operation of the mechanism herein disclosed will be obvious to those skilled in the art. However for purposes of convenience, the sequence of operations of the spindles to fashion one specific form of stocking fabric will be summarized as follows. It will be understood that the mechanism of the invention is not limited to this sequence of operations and that others may be followed to produce other fashionings.

At the completion of a set of stocking fabric blanks

the carrier rods are operated to remove the active yarn carriers from the knitting field and after severing the yarns, the machine is operated to press or knit off the blanks from the needles in the usual manner, and the machine then stopped. At this time the nut 82 for the end stops 85 and the nuts 90 for the point comb rods 89 are at the limit of their inward or narrowing movement. As the machine is operated to knit off the blanks, the chain 204 is advanced one link to place a button 306 of intermediate height beneath each of the levers 299 to position the plate cams and control levers to move the pawls 97, 180 and 207, 271 to laid out positions with respect to the ratchet wheels 96 and 206, respectively. Also during this advance of the chain 204, high buttons 306 are moved beneath the levers 396 to position the plate cams and control levers to move the pawls 137, 192 and 256, 276 to idle positions in relation to the ratchet wheels 140 and 257, respectively. The push button switch 688 is then operated to close and energize the holding circuit through the winding 685 to close the circuit through the relay switch 679. Closing of the switch 679 energizes the solenoid 552 to shift the clutch 536 and connect the sprocket wheel 530 to the shaft 527, energizes the solenoid 577 to disengage the detent 463 from the notched disc 461, and starts the unit 525 to operate the sprocket wheel and turn the spindle 81 in the counterclockwise direction (Fig. 37) to reset the nut 82. As the nut 82 reaches its position for the start of a new set of stocking blanks the rod 560 engages and depresses the button 557 to open the limit switch 687 to deenergize the winding 685 and open the switch 679 which in turn opens the push button switch 688 as hereinbefore set forth. Opening the switch 679 deenergizes the circuit through the solenoids 552 and 577 and the unit 525 to disengage the clutch 536 from the sprocket wheel 530, reengage the detent with the disc 461 and stop further resetting movement of the spindle 81.

During the knitting of the welt portions of a new set of stocking blanks, the chain 204 is advanced another link to move low buttons 306 beneath the levers 299 for the pawls for the spindle 81 to hold the pawls 97 and 207 out of engagement with the teeth of the ratchet wheels 96 and 206, respectively, and to permit engagement of the pawls 180 and 271 with the ratchet wheels 96 and 206, respectively, as shown in Figs. 9 and 10. During the latter advance of the chain 204, high buttons are moved beneath the levers 396 for the pawls 137 and 192 for the spindle 86, to maintain these pawls in idle position in relation to the ratchet wheels 140 and 257. Also at this time no buttons are on the chain for the levers 396 for the plate cams 410 and 450 which positions the low portion 411 of the cam 410 in engagement with the control lever 405 for the pawl 256 and positions the low portion 451 of the cam 450 in engagement with the control lever 446 for the pawl 276. The chain 204 also carries a button 203 to operate the pattern lever 278, link 263 and lever 262 and shift the follower 170 on lever 166 into alignment with the cam 175. Therefore, as the welt is knitted the cam 175 operates the actuator member 150 and the pawls 256 and 276 to turn the spindle 86 a distance of three teeth of the ratchet wheel 257 in the counterclockwise or widening direction on both the "up" and "down" strokes, respectively, of the actuator member to reset the nuts 90 and point combs outwardly to starting position. At the end of the resetting movement of the spindle 86, high buttons 306 on the chain 204 are moved beneath the levers 396 for pawls 256 and 276 to move these pawls to idle position with respect to the ratchet wheel 257 and the button 203 is removed from beneath the lever 278 to permit the follower 170 to return to its position of Fig. 7.

As knitting of the fabrics continues, the welt is completed and turned and the chain 204 is advanced to condition the spindle mechanism for forming the flare or knee narrowings and the leg narrowings. To so con-

dition the spindle mechanism, low buttons 306 on the chain 204 remain beneath the pattern levers 299 for the pawls 180, 207 and 271 and the button is removed from beneath the lever 299 for the pawl 97 which permits engagement of this pawl with the ratchet wheel 96 on the spindle 81 as shown in Fig. 10. Also high buttons 306 remain beneath the pattern levers 396 for the pawls 192, 256 and 276 and a low button engages the lever 396 for the pawl 137 to position the pawl relative to the ratchet wheel 140 as shown in Fig. 12. At this time the followers 127 and 170 are positioned as in Fig. 7. With the parts in these positions, when the camshaft 75 is shifted to its narrowing position by the pattern chain mechanism 70 as hereinbefore set forth, the pawl 97 will turn the spindle 81 a distance of one tooth of the ratchet wheel 96 in the narrowing direction and the pawl 137 turns the spindle 86 a distance of two teeth of the ratchet wheel 140 in the same direction.

After completion of the leg narrowings and prior to widening of the heel portions of the stocking fabrics, the chain 204 is advanced to remove the buttons from beneath the pattern levers 396 for the pawls 137 and 192 for the spindle 86 and a button 203 is moved beneath the pattern lever 278 to shift the follower 170 into alignment with the cam 175. At this time the pawls for the spindle 81 and the remaining pawls for the spindle 86 are in the same position as during the formation of the flare and leg narrowings. As knitting continues, the pawls 137 and 192 turn the spindle 86 distances of three teeth on both "up" and "down" strokes of the actuator member 150 to idly reset the point combs inwardly or in the narrowing direction to increase the number of points subsequently participating in the outward transfer of loops to widen the heel portion of the fabrics. When the resetting of the point combs is completed the chain 204 is advanced to position a high button 306 beneath the levers 396 for the pawls 137 and 192 to again idle these pawls and the button is removed from beneath the lever 278 to permit the follower to again return to its position of Fig. 7.

To start the heel widenings the chain is advanced to move the low button 306 from beneath the pattern lever 299 for the pawl 207 for the spindle 81, a button 306 of intermediate height is moved beneath the lever 396 for the pawl 256 and a button 203 is moved beneath the lever 224 to shift the follower 127 into alignment with the cam 132. In this position the pawl 207 is engaged with the ratchet wheel 206 to turn the spindle 81 a distance of one tooth in the counterclockwise direction when the cam 132 operates the actuator member 105 during a knitting revolution of the camshaft 75. During the next revolution of the camshaft 75 the camshaft is shifted to its narrowing position by the pattern chain mechanism to move the cam 132 out of alignment with the follower 127 to idle the actuator member 105 and to move the cam 172 into alignment with the follower 170 on the lever 166. As the camshaft is rotated the lever 166 operates the actuator member 150 and pawl 256 to turn the spindle 86 a distance of one tooth of ratchet wheel 257 to transfer the loops engaged by the point combs one needle space in the widening direction. Immediately following the outward transfer of the heel loops the chain 204 is advanced one link which moves a low button beneath the pattern lever 299 for the pawl 207 to move this pawl to idle position and removes the button 203 from beneath the lever 224 which permits the follower 127 to return to its position of Fig. 7.

Following a subsequently knitted course the camshaft is again shifted to its narrowing position and the lever 166 operates the actuator member 150 to move the pawl 256 and turn the spindle 86 to move the point combs to transfer the heel loops another one needle distance in the widening direction. In subsequent revolutions of the camshaft buttons on the chain 204 condition the pawls

for operating the spindles 81 and 86 and the camshaft is shifted to narrowing position by the pattern chain mechanism 70 to repeat the desired number of widening operations.

Immediately following the last widening operation the point combs are moved idly outwardly to rest the combs for the start of the sole narrowings. For this purpose the buttons are removed from beneath the pattern levers 396 for the pawls 256 and 276 and a button 203 is moved beneath the pattern lever 278 to shift the follower 170 into alignment with the cam 175. During knitting of the next few courses of loops, the cam 175 operates the actuator member 150 and pawls 256 and 276 turn the spindle three teeth on the "up" and "down" stroke, respectively. When the point combs have been reset to the position for the start of the sole narrowings, the chain 204 is advanced a link to position high buttons 306 beneath the levers 396 for the pawls 256 and 276 to idle these pawls, a low button is moved beneath the lever 396 for the pawl 137, the button is removed from beneath the lever 299 for the pawl 97 and the button 203 is removed from beneath the lever 278 to permit the follower 170 to return to its position of Fig. 7. Thereupon, when the camshaft 75 is shifted to its narrowing position, the pawl 97 turns the spindle 81 a distance of one tooth of the ratchet wheel 96 in the clockwise direction and the pawl 137 turns the spindle 86 a distance of two teeth of the ratchet wheel 140 to form the sole fashionings.

Following the last sole fashioning, the spindle 86 is turned clockwise to idly reposition the point combs inwardly for the start of the toe narrowings. To accomplish this the chain is advanced a link to move a low button 306 into engagement with the pattern lever 396 for the pawl 192 and a button 203 is moved beneath the lever 278 to shift the follower 170 into engagement with the cam 175. At this time a low button 306 is beneath the lever 396 for the pawl 137. With the parts in this position, during each knitting cycle the actuator member 150 operates the pawls 137 and 192 to turn the spindle 86 a distance of two teeth of ratchet wheel 140 on both the "up" and "down" strokes of the actuator member to reset the point combs inwardly. When resetting of the point combs is completed the chain 204 is advanced to move a high button 306 beneath the lever 396 for the pawl 192 to idle this pawl, to move a button of intermediate height beneath the lever 396 for the pawl 276 and to remove the button 203 from engagement with the lever 278 to permit the return of the follower 170 to its position of Fig. 7. At this time, no button is beneath the lever 299 for the pawl 97.

With the parts in this position, when the camshaft 75 is shifted to its narrowing position, the cam 131 operates the actuator member 105 and the pawl 97 to turn the spindle a distance of one tooth of the ratchet wheel 96 and the cam 172 operates the actuator member 150. During the "up" stroke of the actuator member 150 the pawl 137 turns the spindle 86 a distance of two teeth of the ratchet wheel 140 in the clockwise direction to transfer the loops inwardly two needle spaces. During the "down" stroke of the actuator member 150 the pawl 276 turns the spindle 86 a distance of one tooth of the ratchet wheel 257 to idly move the point combs outwardly one needle space whereby one less loop is engaged and transferred in the next narrowing operation. Therefore each of the subsequently formed fashioning marks in one needle closer to the selvage edge than the immediately preceding fashion mark.

After a predetermined number of two needle inward and one needle outward movements of the point combs the direction of the fashioning marks is changed to extend parallel to the selvage edges of the fabrics. To change the direction of the fashion marks the chain 204 is advanced to move a high button beneath the pattern lever 396 for the pawl 276 so that no idle outward move-

ment of the point combs occurs after the inward movement of the combs by the pawl 137 to fashion the fabric. Near the end of the toe portion of the stocking fabrics, the direction of the fashion marks is again changed by conditioning the pawl 276 to again idly move the point combs outwardly a distance of one needle after each inward movement of the combs to fashion the fabrics. When the toe portions of the stocking fabrics have been reduced or narrowed to the desired width, the chain 204 is advanced to move high buttons beneath the pattern levers 299 and 396 to move all of the pawls for the spindles 81 and 86, respectively, to inactive position with respect to their associated ratchet wheels. With the pawls so positioned the machine is again in condition for resetting the spindle 81 by means of the unit 525 as hereinbefore set forth.

It will be understood that the improvements specifically shown and described by which the above described results are obtained, can be changed and modified in various ways without departing from the invention herein disclosed and hereinafter claimed.

I claim:

1. In a full-fashioned knitting machine having a fashioning mechanism including yarn carrier rods, point combs, a threaded spindle for controlling reciprocating movements of said yarn carrier rods, a threaded spindle for controlling movements of the point combs, an actuator member for said yarn carrier rod spindle, means for moving said actuator member in opposite directions, an actuator member for said point comb spindle, means for moving said actuator for said point comb spindle in opposite directions, means connected to and operated by the actuator member for said yarn carrier rod spindle for turning said spindle in opposite directions during both directions of movement of its actuator member, means connected to and operated by the actuator member for the said point comb spindle for turning said spindle in opposite directions during both directions of movement of its actuator member, and pattern means for controlling the operation of said turning means by said actuator members to turn said spindles.

2. In a full-fashioned knitting machine having a fashioning mechanism including yarn carrier rods, point combs, a threaded spindle for controlling reciprocating movements of the carrier rods, a threaded spindle for controlling movements of the point combs, a plurality of means for rotating said carrier rod spindle, a plurality of means for rotating said point comb spindle, an actuator member for operating said rotating means for said carrier rod spindle, an actuator member for operating said point comb spindle, means on said carrier rod spindle controlling the operation of each of said rotating means for said carrier rod spindle, means on said point comb spindle for controlling the operation of each of said rotating means for the point comb spindle, pattern means, connecting means between each of said controlling means for the rotating means and said pattern means, and means to move said connecting means to inactive position with respect to said pattern means.

3. In a full-fashioned knitting machine operating through knitting and fashioning cycles and having yarn carrier rods, point combs, a spindle for controlling reciprocating movements of the yarn carrier rods, a spindle for controlling movements of the point combs, an actuator member for said yarn carrier rod spindle, means for moving said actuator member in opposite directions, an actuator member for the point comb spindle, means for moving said actuator member in opposite directions, means operated by the actuator member for said yarn carrier rod spindle for turning said spindle during both directions of movement of said actuator, means operated by the actuator member for said point comb spindle for turning said spindle during both directions of movement of said actuator, and means for operating said actuator

members through said movements in both directions during both said knitting and fashioning cycles.

4. In a full-fashioned knitting machine operating through knitting and fashioning cycles and having yarn carrier rods, point combs, a spindle for controlling reciprocating movements of the yarn carrier rods, a spindle for controlling movements of the point combs, an actuator member for said carrier rod spindle, means for moving said actuator member in opposite directions, an actuator member for the point comb spindle, means for moving said actuator member for the point comb spindle in opposite directions, means operated by the actuator member for said yarn carrier rod spindle for turning said spindle during both directions of movement of said actuator member, means operated by the actuator member for said point comb spindle for turning said spindle during both directions of movement of said actuator member, means for operating said actuator members through said movements in both directions during both knitting and fashioning cycles, and control means for said operating means for said actuator members.

5. In a full-fashioned knitting machine having fashioning mechanism including yarn carrier rods, point combs, a threaded spindle for controlling reciprocating movements of said yarn carrier rods, a threaded spindle for controlling movements of said point combs, an actuator member for said carrier rod spindle having up and down movements, an actuator member for said point comb spindle having up and down movements, pawls connected to and operated by said actuator member for said carrier rod spindle for turning said spindle in opposite directions during up and down movements of said actuator member, means for controlling the operation of said pawls to turn said carrier rod spindle through distances of the same extent, pawls connected to and operated by said actuator member for said point comb spindle for turning said spindle in opposite directions during up and down movements of said actuator member, and means for controlling the operation of said pawls to turn said point comb spindle through distances of different extent.

6. In a full-fashioned knitting machine having fashioning mechanism including yarn carrier rods, point combs, a spindle for controlling reciprocating movements of said carrier rods, a spindle for controlling movements of said point combs, an actuator member for said carrier rod spindle having up and down movements, an actuator member for said point comb spindle having up and down movements, a plurality of pawls connected to and operated by each of the actuator members for said spindles on the up movements of said actuator members, a plurality of pawls connected to and operated by each of the actuator members for said spindles on the down movements of said actuator members, a member for controlling the operation of each of the pawls connected to the actuator member for said carrier rod spindle for turning said spindle in opposite directions through distances of the same extent, and a member for controlling the operation of each of the pawls connected to the actuator member for the point comb spindle for turning said spindle in opposite directions through a plurality of distances of different extent.

7. In a full-fashioned knitting machine having fashioning mechanism including yarn carrier rods, point combs, a threaded spindle for controlling reciprocating movements of said yarn carrier rods, a threaded spindle for controlling movements of the point combs, an actuator member for said yarn carrier rod spindle having up and down movements, an actuator member for said point comb spindle having up and down movements, pawls connected to said actuator member for said yarn carrier rod spindle for turning said spindle during both the up and down movements of said actuator member, pattern means for controlling the operation of said pawls to turn said yarn carrier rod spindle in opposite directions

through distances of the same extent, pawls connected to and operated by said actuator member for said point comb spindle during the up and down movements of said actuator member, and pattern means for controlling the operation of said pawls to turn said point comb spindle in opposite directions through distances of different extent.

8. In a full-fashioned knitting machine having means for knitting and fashioning stocking fabric blanks, a cam-shaft having a knitting position and a fashioning position, said fashioning means including reciprocating yarn carrier rods, point combs, a threaded spindle for controlling the reciprocating movements of the yarn carrier rods, a threaded spindle for controlling the movements of the point combs, a plurality of pawls for turning the spindle for the yarn carrier rods in a narrowing direction, a plurality of pawls for turning said yarn carrier rod spindle in a widening direction, a plurality of pawls for turning said point comb spindle in a narrowing direction, a plurality of pawls for turning said point comb spindle in a widening direction, pattern means for determining the operation of each of said pawls for said spindles, and cam means on said cam-shaft for operating said pawls in both said knitting and fashioning positions of said cam-shaft.

9. In a full-fashioned knitting machine having fashioning means including reciprocating yarn carrier rods, point combs, a threaded spindle for controlling the reciprocating movements of said yarn carrier rods, a threaded spindle for controlling the movements of the point combs, the combination with an actuator member, means for operating said actuator member, pawls for turning said yarn carrier rod spindle in opposite directions during a portion of the operating movement of said actuator member, pawls for turning said yarn carrier spindle during another portion of the operating movement of said actuator member, a second actuator member, means for operating said second actuator member, pawls connected to and operated by said second actuator member during a portion of the operating movement thereof for turning the point comb spindle in opposite directions, pawls connected to and operated by said second actuator member during another portion of the operating movement thereof for turning said point comb spindle in opposite directions, cam means on said spindles for controlling the operation of each of said pawls and pattern means for positioning said cam means to selectively determine the operation of said pawls.

10. In a full-fashioned knitting machine operating through knitting and fashioning cycles and having yarn carrier rods, point combs, a spindle for controlling reciprocating movements of the yarn carrier rods, a spindle for controlling movements of the point combs, ratchet wheels having oppositely disposed teeth on said yarn carrier rod spindle, pawls associated with said ratchet wheels on said yarn carrier rod spindle, ratchet wheels having oppositely disposed teeth on said point comb spindle, pawls associated with said ratchet wheels on said point comb spindle, an actuator member for the pawls for said carrier rod spindle having up and down movements, said actuator member adapted to operate certain of the pawls on said up movement and certain of said pawls on said down movement for turning said yarn carrier rod spindles in opposite directions, an actuator member for the pawls for said point comb spindle, said latter actuator member adapted to operate certain of the pawls on said up movement and certain of said pawls on said down movement to turn said point comb spindle in opposite directions, pattern means for controlling the engagement of the pawls with said ratchet wheels to turn said spindles, means for operating said actuator members during fashioning cycles of the machine, means for operating said actuator members during knitting cycles of the machine, and pattern means for controlling the operation of said actuator member operating means.

11. In a full-fashioned knitting machine having fashioning mechanism including yarn carrier rods, point combs, a spindle for controlling reciprocating movements of the yarn carrier rods, a spindle for controlling movements of the point combs, ratchet wheels on said yarn carrier rod spindle, ratchet wheels on said point comb spindle, pawls associated with the ratchet wheels on said yarn carrier rod spindle, pawls associated with the ratchet wheels on said point comb spindle, an actuator member having up and down movements and connected to the pawls for said point comb spindle, said actuator member adapted to operate certain of the pawls during the up movements and the other pawls on the down movements thereof to turn the yarn carrier rod spindle in opposite directions, a second actuator member having up and down movements and connected to the pawls for said point comb spindle, said second actuator member adapted to operate certain of the pawls during the up movements and certain of the pawls during the down movements thereof to turn said point comb spindle in opposite directions, means on said yarn carrier rod spindle for controlling the engagement of the pawls with the ratchet wheels thereon to turn said spindle the same distance during each up and down movement of said actuator member, and means on said point comb spindle for controlling the engagement of the pawls with the ratchet wheels thereon to turn said spindle a plurality of different distances during each up and down movement of said second actuator member.

12. In a knitting machine having fashioning mechanism including reciprocating yarn carrier rods, point combs, a spindle for controlling the reciprocating movements of said carrier rods, a spindle for controlling movements of said point combs, actuator members having up and down movements, ratchet wheels on said spindles, pawls adjusted to engage said ratchet wheels and operated by the actuator members to turn said spindles in opposite directions during up movements of said actuator members, pawls adapted to engage said ratchet wheels and operated by the actuator members to turn said spindles in opposite directions during down movements of said actuator members, cam means for determining active and inactive positions of said pawls with respect to said ratchet wheels, said cam means acting to prevent turning movement of said spindles by said inactive pawls during up and down movements of said actuator members but permitting engagement of said inactive pawls with said ratchet wheels at the end of said up and down movements of said actuator members to limit the turning movements of said spindles by said active pawls.

13. In a knitting machine operating through knitting and fashioning cycles and having reciprocating yarn carrier rods, point combs, and a fashioning head mechanism for controlling the reciprocating movements of said carrier rods and for operating said point combs including a spindle for said carrier rods, a spindle for said point combs, actuator members for said spindles having up and down movements, pawls connected to and operated by the actuator members to turn said spindles in opposite directions during the up movements of said actuator members, pawls connected to and operated by the actuator members to turn said spindles in opposite directions during the down movements of said actuator members, cam means on said spindles for determining active and inactive positions of said pawls, said inactive pawls acting on the up movements of said actuator members to limit the turning movements of the spindles by the active pawls, and said inactive pawls acting on the down movements of said actuator members to limit the turning movements of said spindles by the active pawls, said cam means also acting to position said latter pawls to hold said spindles against movement between operating movements of said actuator members.

14. In a knitting machine having fashioning means including, reciprocating yarn carrier rods, point combs, a threaded spindle, a nut on said spindle having end stops

31

for controlling the reciprocating movements of said yarn carrier rods, means associated with said yarn carrier rod spindle for turning the spindle in either direction, a threaded spindle for said point combs, means associated with said point comb spindle for turning the spindle in either direction, means for deactivating said turning means for the carrier rod spindle, a motor for turning said yarn carrier rod spindle in one direction for resetting the end stop nut for said yarn carrier rods when said turning means is deactivated, an electric circuit for said motor, and means carried by said nut for opening said circuit to stop the motor when said end stop nut has reached its reset position.

15. In a knitting machine having fashioning means including, reciprocating yarn carrier rods, point combs, a threaded spindle, a nut on said spindle for controlling the reciprocating movements of said yarn carrier rods, a threaded spindle for said point combs, pawls associated with said spindles and having active and inactive positions with respect to said spindles, cam means on said spindles for determining said active and inactive positions of said pawls, an actuator member connected to the pawls associated with each of said spindles and for operating said pawls when in active position to turn said spindles in opposite directions, a motor for turning the yarn carrier rod spindle in one direction to reset the end stop nut, said cam means on said yarn carrier rod spindle acting to move the pawls associated with said carrier rod spindle to inactive position when said motor operates to turn said spindle.

16. In a knitting machine having fashioning means including, reciprocating yarn carrier rods, point combs, a threaded spindle, a nut on said spindle having end stops for controlling the reciprocating movements of said yarn carrier rods, a threaded spindle for said point combs, pawls associated with said spindles, an actuator member for operating the pawls associated with each of said spindles, an electric motor for turning the yarn carrier rod spindle in one direction to reset the end stop nut for said yarn carrier rods, an electric circuit for said motor, a switch for closing said circuit to start said motor, a second switch in said circuit and means carried by said end stop nut for operating said second switch to open said circuit to stop said motor when said end stop nut has reached its reset position.

17. In a knitting machine having fashioning means including, reciprocating yarn carrier rods, point combs, a threaded spindle, a nut on said spindle having end stops for controlling the reciprocating movements of said yarn carrier rods, a threaded spindle for said point combs, pawls associated with said spindles, an actuator member for operating the pawls associated with each of said spindles to turn said spindles in opposite directions, an electric motor for turning the yarn carrier rod spindle in one direction to reset the end stop nut, means including a clutch for connecting said motor to said yarn carrier rod spindle, an electric circuit for said motor, a switch in said electrical circuit for closing and energizing said circuit to start said motor, a solenoid in said circuit for operating said clutch to connect said motor to said yarn carrier rod spindle when said circuit is closed, a second switch in said circuit, and means carried by said end stop nut for operating said second switch to deenergize said circuit to stop said motor and to permit said solenoid to disengage said clutch when said nut has reached its reset position.

18. In a knitting machine operating through knitting and fashioning cycles and having reciprocating yarn carrier rods, point combs, a spindle, a nut on said spindle having end stops for controlling the reciprocating movements of said yarn carrier rods, a threaded spindle for controlling movements of said point combs, pawls for turning said spindles in opposite directions, actuator members for operating said pawls, cam means on said spindles for determining active and inactive positions of said pawls,

32

a notched disc on each of said spindles, detent members engaging said notched discs, an electric motor, a normally open electric circuit for said motor, a switch in said circuit for closing said circuit to start said motor, means in said circuit for connecting said motor to said spindle for said carrier rod end stop nut to turn said spindle in one direction to reset said nut thereon, means connected in said circuit for disengaging the detent member on said spindle for said carrier rod end stop nut from said notched disc on said spindle during operation of said motor to turn said spindle, a second switch in said circuit, and means on said nut for operating said second switch when said nut is in its reset position to open said circuit to stop said motor, to disconnect said motor from said spindle and to reengage said detent member with said notched disc.

19. In a full-fashioned knitting machine having fashioning means including yarn carrier rods, point combs, a threaded spindle for controlling reciprocating movements of said yarn carrier rods, a threaded spindle for controlling movements of the point combs, an actuator member for said carrier rod spindle having up and down movements, an actuator member for said point comb spindle having up and down movements, means connected to and operated by said actuator member for said carrier rod spindle for turning said spindle in opposite directions during the up and down movements of the actuator member, means connected to and operated by said actuator member for said point comb spindle for turning said spindle in opposite directions during the up and down movements of the actuator member, and means for controlling said spindle turning means to limit the turning movements of said spindles by said turning means.

20. In a full-fashioned knitting machine having fashioning means including yarn carrier rods, point combs, a threaded spindle for controlling reciprocating movements of said yarn carrier rods, a threaded spindle for controlling movements of said point combs, an actuator member for said carrier rod spindle having up and down movements, an actuator member for said point comb spindle having up and down movements, means connected to and operated by said actuator member for said carrier rod spindle for turning said spindle in opposite directions during the up and down movements of the actuator member, means connected to and operated by said actuator member for said point comb spindle for turning said spindle in opposite directions during the up and down movements of the actuator member, and means for controlling said spindle turning means to hold said spindles against turning movements between operating movements of said actuator members.

21. In a knitting machine having fashioning means including, reciprocating yarn carrier rods, a threaded spindle, a nut on said spindle having end stops for controlling the reciprocating movements of said yarn carrier rods, means associated with said spindle for turning the spindle in opposite directions, means for deactivating said turning means for said spindle, a motor for turning said spindle in one direction for resetting said nut when said turning means is deactivated, an electric circuit for said motor, and means operated by said nut to open said circuit and stop said motor when said nut has reached its reset position.
